UNITED STATES PATENT OFFICE.

JONATHAN BOOTHMAN, OF CHEETHAM, ENGLAND.

NAIL CUTTING AND DRIVING MACHINE.

SPECIFICATION forming part of Letters Patent No. 596,048, dated December 28, 1897.

Application filed May 10, 1897. Serial No. 635,898. (No model.)

To all whom it may concern:

Be it known that I, JONATHAN BOOTHMAN, a subject of the Queen of Great Britain and Ireland, and a resident of 361 St. Luke's Terrace, Cheetham, near Manchester, county of Lancaster, England, have invented certain Improvements in or Applicable to Nail Cutting and Driving Machines, of which the following is a specification.

10 My said invention relates to improvements in or applicable to machines for forming nails from a continuous length of wire and driving them into boots and other articles.

15 The object of this invention is to improve machines which use in combination two reversely-inclined cutters, one being fixed and the other reciprocating, by further combining therewith reciprocating means of supplying the nail to be driven and making the cutter-bar of the said reciprocating cutter present a driver hole or passage in line with the said carrier and the fixed outlet or feed-hole leading from the latter.

20 To this end my invention consists in the construction and combination of parts hereinafter set forth and claimed.

25 In the drawings, Figure 1 is a front elevation of the lower part of a nail making and driving machine, showing the wire in position to be cut. Fig. 2 is a sectional plan through $x x$ of Fig. 1. Fig. 3 is a front elevation corresponding to Fig. 1, but showing the parts in their relative positions when the nail is being driven. Fig. 4 is a sectional plan 30 through $x' x'$ of Fig. 3. Fig. 5 is a transverse section through $y y$ of Fig. 1. Figs. 6 and 7 show plan and elevation, respectively, of the cutters and nozzle or nail-carrier to be hereinafter described. Figs. 8 and 9 show front 35 and side elevation of a nail having the inclined point formed on the broad side of the wire.

40 In the drawings only so much of a machine is shown as is necessary to illustrate the application of my said invention. Nail cutting and driving machines having reciprocating cutters of several kinds operated by horizontal levers actuated by cams on the driving-shaft of the machine are well known.

45 The driver-head works in the usual guiding-groove 1. The point of the driver 2 passes through the driving-hole 3. A vertical hole 12,

known as the "feeding-hole," made through a bracket or slide-bar carrier c , hereinafter described, and through a block or nozzle 13, 55 fixed to the latter, is in the same vertical plane with driving-hole 3, longitudinal of the cutter-holder 8^a, in which the said vertical driving-hole 3 is made, and also in the same transverse vertical plane with the bore of nail-carrier 7 in the line of reciprocation of the latter. At a certain point of the throw of the nail-carrier slide 7^a and the cutter-holder 8^a the said driving-hole, feeding-hole, and nail-carrier bore register, so as to make a continuous vertical passage for the driver-point and 60 nails.

50 A fixed cutter 4, having an inclined cutting edge at 4^a, (see Fig. 7 for detail,) is secured by set-screws 5 in the frame 6 of the machine. The wire w is fed down behind the inner face of the fixed cutter 4 and in front of the inclined edge of the reciprocating cutter 8, as shown in Figs. 6 and 7. The reciprocating cutter 8 is secured to the cutter-holder 8^a by means of set-screws 8^b.

55 A nozzle or nail-carrier 7, through which the nails pass and which transports the cut nails from the place where they are formed to the driver, is mounted in the slide-bar 7^a, 70 which has a rectilinear reciprocating motion parallel to the front of the machine, while the sliding cutter 8 has a rectilinear reciprocating motion at right angles thereto—that is to say, to and from the front of the machine instead of from left to right, and vice versa, 75 as has hitherto been the case. The nail is thus at once formed with its penetrating edge normal to the edge of the article into which it is to be driven. When the nail has 80 been cut, the waste piece 14 of the wire is carried forward in front of the reciprocating cutter 8, until, reaching the front edge of the machine, it falls into the usual tray or chute conveniently placed to receive the waste. 85

80 c is a bracket, secured to the frame 6 by means of set-screws c' , and forms a carrier or support for the slide-bar 7^a.

85 Mounted on the table a , Figs. 1 to 4, is an oscillating lever 9 connected at 11 to the 90 slide-bar 7^a, which, when operated by means of a cam on the main driving-shaft, imparts a reciprocating motion to the slide 7^a. A bell-crank lever 10, also mounted on the ta- 95

ble *a* of the machine, also worked by a cam on the main driving-shaft, operates the reciprocating cutter 8.

Assuming the parts to be in the position shown in Figs. 1 and 2 and the wire to have been threaded right through the nozzle or nail-carrier 7, the reciprocating cutter 8 is caused by means of the bell-crank lever 10 to travel forward in the direction of the arrow *b*, Fig. 2, whereupon the lower end of the wire *w* is severed by the joint action of the fixed cutter 4 and the reciprocating cutter 8. The lower end of the wire having been severed remains in the nozzle or nail-carrier 7 until it comes under the driving-hole 3 and over the orifice in the stationary nozzle 13, as shown in Figs. 3 and 4, thus forming a continuous passage for the descent of the driving-pin. When this position is attained, the driving-pin 2 descends and the nail is driven into the boot or other article. The slide 7^a and the reciprocating cutter 8 next move back into the position shown in Figs. 1 and 2. The wire is fed downward by the usual feed-rolls, and the same sequence of operations takes place.

By the said means flat taper-pointed nails may be cut from flat wire with the incline on the broad side of the wire, as shown in Figs. 8 and 9, while at the same time enabling them to be driven with the narrow sides of the nails parallel to the edge of the article operated upon.

What I claim as my invention, and desire 35 to secure by Letters Patent, is—

1. In a nail making and driving machine the combination of a reciprocating cutter and its cutter-bar the latter having a driving-hole formed therein, with a fixed cutter, a reciprocating nail-carrier and means for allowing the passage of the nail therefrom out of the machine the said driving-hole, the bore of the nail-carrier and the outlet-passage being arranged to register in a certain position of the reciprocating parts substantially as set forth.
2. In a nail cutting and driving machine the combination of a fixed cutter 4, a rectilinear reciprocating cutter 8^a having a driving-hole 3 therein, a reciprocating slide-bar 7^a and nail-carrier 7 moving therewith and a fixed part having a feed-hole with which the said driving-hole and the bore of the said carrier are arranged to register substantially as set forth.
3. In a nail making and driving machine, a cutter-bar and a nail-carrier reciprocating at right angles to each other and a fixed nozzle having a feed-hole arranged to register with the bore of the said carrier and with a driving-hole in the said cutter-bar substantially as set forth.

In testimony whereof I have signed my name to this specification in the presence of two subscribing witnesses.

JONATHAN BOOTHMAN.
